TILLER ARRANGEMENT FOR SAILBOATS
Jack H. Brazier, Fort Myers, Fla., assignor to Sears, Roebuck and Co., Chicago, Ill., a corporation of New York

Filed Dec. 17, 1965, Ser. No. 524,989
4 Claims. (Cl. 74—501.5)

ABSTRACT OF THE DISCLOSURE

A tiller arrangement especially suitable for small sailing craft, designed to facilitate control of the rudder under all conditions with minimum transverse movement of the tiller; at any selected horizontal angle, wherein the tiller is pivoted on a horizontal axis, permitting it to be elevated out of the way of the steersman and there rotated in disconnected relation to the rudder, while in its lowered position the tiller is operatively connected to the rudder. This connection is accomplished by means of interengageable elements on the lower part of the tiller and on a horizontally rotatable member, respectively, adjacent the deck, said last mentioned member being connected to the rudder for transmitting to it horizontal movement of the tiller.

My invention relates to steering devices for sailing craft, and has especially to do with a tiller arrangement which is especially suitable for small sailboats of single- or multiple-rudder design.

Small sailboats are notoriously uncomfortable by reason of the limited space and the limitations of physical movement in sailing the craft. Such physical movement is aggravated by the amount of rotary tiller travel and by the necessity of holding the tiller at a fixed angle while shifting body weight, as in coming about and jibbing.

To hold the tiller in a fixed position while moving from a midships position to a hiked out position, is extremely difficult. Accordingly, supplementary tiller extensions (hiking sticks) are frequently provided for added convenience.

An object of my invention is to provide a tiller arrangement which will enable the steersman to control the rudder under all conditions with minimum transverse movement of the tiller and at any selected angle to suit the convenience of the operator.

Still another object is to provide an arrangement of the type referred to which will permit raising the tiller to an upstanding position out of the line of contact with the operator's body and simultaneously disconnecting same from operative connection with the rudder controlling apparatus, whereby the tiller may be rotated in such disconnected condition, without risk of contact with the operator and without necessitating movement of the body to avoid such contact, and then subsequently reconnecting the tiller with said steering apparatus at a convenient angle.

Still another object is to provide a mechanism of the type referred to which will be simple and inexpensive in construction, rugged and fool-proof in operation, and generally satisfactory for the purposes desired.

Additional objects and advantages will become apparent as the description proceeds.

Referring now to the drawings forming a part of this specification and illustrating a preferred embodiment of my invention,

FIG. 1 is a perspective view of a small sailing craft to which my invention is applied;

FIG. 2 is a fragmentary enlarged perspective view showing the lower portion of a tiller and associated parts

2

of a steering mechanism, as embodied in the craft of FIG. 1;

FIG. 3 is a top plan-section of the parts connected to the tiller as seen in FIG. 2, and as taken substantially along line 3—3 of FIG. 4;

FIG. 4 is a vertical sectional-elevational view taken substantially along line 4—4 of FIG. 3, the tiller being shown in raised or disconnected position, and

FIG. 5 is a view similar to FIG. 4 but showing the tiller in lowered or connected position in relation to the associated mechanism.

Numeral 10 indicates a small sailing craft of any type or description to which my invention is applicable. A tiller 15, which may be of any desired type and construction, is mounted on the stern deck. An elongated recess 17 may be provided to receive the mechanism hereinafter described for controlling rudder R, although not required by my invention.

The tiller may be a rod of generally angular shape as seen in FIG. 1, and may be formed of wood or metal, preferably tubular stock of steel, aluminum, etc., the lower extremity of tiller 15 being seated in a sleeve portion 18 which may be part of a casting having oppositely extending pintle portions 22 and also an integral radially extending pawl portion 24.

Pawl 24 is engageable with a ratchet 27 which, in turn, is integral with a pulley 30, said pulley-ratchet being rotatably mounted on a supporting plate 33 by means to be described, said plate being secured to the deck as by screws 37.

Rotatably mounted on plate 33 as by screw 35 is a circular bushing 39 having integrally formed therewith, as by casting, a pair of opposed upstanding trunnions 42 which journal the pintles 22. Said bushing or trunnion plate 39 serves also as a bearing for pulley 30 by means of interlocking rectangular shoulder portions 45 formed on plate 39 and pulley 30.

Pulley 30, as seen clearly in FIGS. 4 and 5, seats several turns of cable C for transmitting force from the tiller to rudder R.

It will be readily apparent that the tiller 15 may be raised about pintles 22 as an axis to an upstanding position, as seen in FIG. 4, which is out of line with the steersman's body. In that position pawl 24 is out of engagement with ratchet 27 and the tiller may then freely be rotated to any desired angle without effect upon cable C or rudder R, bushing 39 sliding on plate 33. When the tiller is in this condition the operator may, of course, readjust the position of his body in the cockpit or relative to the deck without any inconvenience or any risk of bodily contact with the tiller. After rotation of the tiller to the desired angle, it may then be lowered, bringing pawl 24 into engagement with ratchet 27 at the desired angle and the tiller then rotated in unison with pulley 30 to produce the desired movement of the rudder.

The shape of the tiller contributes to the effectiveness of the combination constituting my invention, the angular form assisting in clearing the helmsman's knees at all times.

Referring to FIG. 5, the two ends of the cable C are secured to pulley 30 as by means of headed screws 52 which serve as clamps to prevent cable slippage. Spring tension means 55 also provide some elasticity in the cable, consisting of a U-shaped retainer for a coil spring inserted in the cable, one end of the cable being secured to a transverse pin reacting on the spring, the latter being retained by flanges on said retainer.

Various changes coming within the spirit of my invention may suggest themselves to those skilled in the art; hence, I do not wish to be limited to the specific embodiments shown and described or uses mentioned, but intend

the same to be merely exemplary, the scope of my invention being limited only by the appended claims. For example, the specific character of the ratchet segment and pawl may be varied widely, or reversed as to their relative positions, so long as radially adjustable interengageable means is provided between the base of the tiller and the pulley.

I claim:

1. In a steering mechanism for a navigable craft, including a direction-control element and flexible means for transmitting motion thereto,

- (a) a pulley operatively connected to said transmission means,
- (b) means for rotatably mounting said pulley on a surface of the craft including
- (c) a bearing rotatably seating said pulley,
- (d) a manual steering element,
- (e) means connecting said steering element to said bearing and permitting rotary movement of the steering element in a vertical plane, and
- (f) interconnecting means on said steering element and said pulley, respectively, operative when the steering element is in lowered position to permit transmission of motion from the steering element to the direction control element.

2. In a steering mechanism for a navigable craft, including a direction-control element and flexible means for transmitting motion thereto,

- (a) a pulley operatively connected to said transmission means,
- (b) means for rotatably mounting said pulley on a surface of the craft,
- (c) a tiller,

(d) means carried by the mounting means for supporting the tiller for movement on a horizontal axis between a lowered operative position and an elevated inoperative position, and

(e) interconnecting means on the tiller and pulley, respectively, engageable only when the tiller is in lowered position, whereby rotation of the tiller on a vertical axis will actuate said direction-control element.

3. A combination as in claim 2, wherein said interconnecting means includes,

- (a) a detent on one of said tiller and pulley and
- (b) an arcuate segment on the other of said tiller and pulley having a series of spaced formations engageable with said detent.

4. A combination as in claim 3, wherein

- (a) said mounting means comprises a base plate and bearing member rotatably supported thereon, and
- (b) said pulley is rotatably retained by the base plate and bearing member,
- (c) the tiller supporting means consisting of interengaging elements carried by the bearing member and tiller, respectively, rotatably mating with each other to permit rotation of the tiller between a raised inoperative position and a lowered position operatively connected to the direction-control element.
